Klaus P. Stoffel(57) CLAIM

The ornamental design for a motor vehicle and/or toy replica, as shown and described.

DESCRIPTION

FIG. 1 is a front, right side perspective view of the motor vehicle and/or toy replica of the present invention;
FIG. 2 is a rear, right side perspective view thereof;
FIG. 3 is a left side view thereof;
FIG. 4 is a right side view thereof;
FIG. 5 is a front view thereof;
FIG. 6 is a rear view thereof; and,
FIG. 7 is a top view thereof.
The wheels shown in broken lines are for illustrative purpose only and form no part of the claim design.
